UNITED STATES PATENT OFFICE

WILLIAM C. McWHIRTER, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA

RAILWAY-CAR RETARDER

Application filed July 19, 1928. Serial No. 293,942.

My invention relates to railway car retarders of the type involving brake beams located in the trackway and movable into engagement with the wheels of a vehicle to retard the motion of the vehicle along the track. More specifically by present invention relates to the structure of the brake beams used in retarders of this character.

I will describe one form of retarded embodying my invention, and will then point out the novel features thereof in claims.

In the accompanying drawing, Fig. 1 is a plan view showing a portion of one form of car retarder embodying my invention. Fig. 2 is a sectional view of the retarder structure shown in Fig. 1. Fig. 3 is a plan view, partly sectioned, and on an enlarged scale, showing the articulating means connecting the brake beam sections of the retarder shown in Fig. 1. Fig. 4 is a side view of a portion of the retarder shown in Fig. 3. Fig. 5 is a sectional view on the line V—V of Fig. 3, looking in the direction indicated by the arrows.

Similar reference characters refer to similar parts in each of the views.

Referring first to Figs. 1 and 2, the reference character 1 designates a track rail, and the reference characters 2 and 3 designate car retarder brake beams located on opposite sides of the rail, respectively, and movable toward and away from the rail. Brake beam 2 is made up of a series of sections 2^a, 2^b, 2^c, etc., and brake beam 3 is similarly made up of a series of sections 3^a, 3^b, 3^c, etc. Each beam section is provided with a plurality of springs G, one end of each spring being connected with the beam section and the other end being pivotally connected at point D with a plate 11 which is fixed to the railroad ties. Each spring G is disposed at an acute angle with respect to the associated brake beam section, and each beam section is movable to the right, as viewed in Fig. 1, into a closed position where- in it engages the sides of the wheel of a vehicle passing through the retarder. When in closed position, the springs associated with each beam section bias the section toward the car wheels. The means for moving the

open positions form no part of my present invention, but one means which may be used for this purpose is illustrated and described in my co-pending application, Serial No. 187,525, filed April 29, 1927.

The normal movement of vehicles through the retarder is in the direction of the arrow in Fig. 1, so that the left-hand end of each beam section may be termed the "forward" end and the right-hand end of each section may be termed the "rear" end.

Projecting rearwardly from the rear end of each section is a tongue 5 which enters a groove 6 in the outside surface of the forward end of the section next in the rear. The inner face of the tongue 5 bears on the inner wall of the groove 6, so that when section 2^a, for example, is occupied by the wheels of a vehicle, this section acts on the tongue 5 of section 2^b, and so tends to open section 2^b against the action of the springs G. The effect of a vehicle wheel in section 3^a is similarly to tend to open section 3^b against the action of the springs G associated with the latter section. In other words, the tongue at the rear end of section 3^b bears on the inner face of the groove in section 3^a. To put the matter in another way, the retarder is made up of right-hand beams and left-hand beams which are not identical, but which are reversed in so far as the tongues and grooves are concerned, so that a car wheel acting on sections 2^a and 3^a has the same effect on section 2^b as it has on section 3^b.

The adjoining ends of the sections of each beam are pivotally connected by a pin 9 which passes through holes 9^a in section 2^a, for example, and through an elongated hole 9^b in the tongue 5 of section 2^b. The purpose of these pins is to articulate the brake beam sections when a vehicle moves through the retarder in the direction opposite to normal. Assume, for example, that a vehicle is moving in the direction opposite to that indicated by the arrow in Fig. 1, and that the wheels of this vehicle occupy retarder sections 2^b and 3^b. These sections will then act through the pins at the right-hand ends thereof to open sections 2^a and 3^a against the action of the springs associated with the latter section,

so that when the wheels pass from section 2^b into section 2^a, for example, there will be no tendency for the wheels to ride onto section 2^a.

5 The inner surface of each tongue 5 is preferably grooved to provide a rolling engagement between this surface and the inner wall of the groove 6 during relative motion of the beam sections 2^a and 2^b. Furthermore, 10 I preferably provide a replaceable wearing shim 8 between the tongue 5 and the walls of the groove 6, this shim being U-shaped in the form here shown. These shims tend to maintain alignment of the braking surfaces and they take up wear at the points of articulation. Each brake beam section is, 15 of course, provided with the usual replaceable brake shoe 4, which is indicated in Fig. 5, but which forms no part of my present invention.

20 One advantage of a brake beam structure embodying my invention, is that it provides liberal wearing surfaces at the articulation points, and another advantage is that 25 it provides definite means for assuring alignment of the brake shoes as a vehicle passes through the retarder. There is no strain on the bolts holding the brake shoes in place on the brake beams as would be the 30 case if the brake shoes were designed to overlap the ends of the brake beams. The pins 9 provide a ready means for disconnecting the brake beam sections. To do this, it is merely necessary to remove these pins and 35 to then move the beam section rearwardly by moving it toward the trackway, thus disengaging the tongue 5 from the recess 6. A beam section may be replaced by a similar operation in the reverse order.

40 Although I have herein shown and described only one form of car retarder structure embodying my invention, it is understood that various changes and modifications may be made therein within the scope of the 45 appended claims without departing from the spirit and scope of my invention.

Having thus described my invention, what I claim is:

1. A car retarder comprising a brake beam 50 made up of a series of sections, springs acting on each section to bias it toward the wheels of a vehicle, the adjoining ends of the sections overlapping in such manner that when the retarder is closed and a vehicle 55 passes through the retarder in the normal direction the section which is occupied by the car will tend to open the next section ahead against the action of its associated springs, and pins connecting the adjoining 60 ends of said sections so that when the retarder is closed and a vehicle passes through it against the normal direction the section which is occupied will tend to open the next section ahead against the action of its biasing 65 springs.

2. A car retarder comprising two brake beams one located on each side of a track rail and each made up of a series of sections, springs acting on each section to bias the section toward the wheels of a vehicle, the 70 adjoining ends of the sections overlapping in such manner that when the retarder is closed and a vehicle passes through the retarder in the normal direction the section which is occupied by the car will tend to open the next section ahead against the action of its associated springs, and pins connecting the adjoining ends of said sections so that when the retarder is closed and a vehicle passes through it against the normal 75 direction the section which is occupied will tend to open the next section ahead against the action of its biasing springs.

3. A car retarder comprising a brake beam made up of a series of sections, springs acting on each section to bias it toward the wheels of a vehicle, a tongue formed on the rear end of each section and entering a groove on the outside of the forward end of the section next in the rear so that when the 80 retarder is closed and a vehicle passes through it in the normal direction the section which is occupied will tend to open the next section ahead against the action of its associated springs, and a pin passing 85 through the lip on each section and the forward end of the next section in the rear so that when the retarder is closed and a vehicle passes through it against the normal direction the section which is occupied will tend to open the next section ahead against the action of its biasing springs.

In testimony whereof I affix my signature.
WILLIAM C. McWHIRTER.
